UNITED STATES PATENT OFFICE.

H. WILLIAM ELLICOTT, OF BALTIMORE, MARYLAND.

HOT-BLAST STOVE FOR BLAST-FURNACES.

SPECIFICATION forming part of Letters Patent No. 276,790, dated May 1, 1883.

Application filed September 8, 1882. (No model.)

To all whom it may concern:

Be it known that I, H. WILLIAM ELLICOTT, of the city of Baltimore, and State of Maryland, have invented certain Improvements in 5 Hot-Blast Stoves for Blast-Furnaces, of which the following is a specification.

This invention consists in the combination, with the ordinary hot-blast pipes in a hot-blast stove or oven, of a gang of pipe situated below the said blast-pipes and in communication therewith, in which the air-blast is primarily heated, combustion-chambers located between the lower sections of the said gang-pipe, into which the hot gases from the furnace are introduced, having slots to allow of the escape of the gases to the upper part of the stove and thence to the stack, and hollow heat-retaining blocks placed over the said combustion-chambers and between the upper 15 portions of the gang, which, in connection with the walls of the stove, prevent rapid fluctuations in temperature of the said air-pipe and distortion of the same, as will hereinafter fully appear.

25 In the drawings forming a part hereof, Figures I and II are vertical sections of a hot-blast stove embodying my improvements, as seen from different points. Fig. III is a sectional plan taken on the dotted line xx , Fig. I. Fig. IV is also a sectional plan taken on the dotted line yy , Fig. VI. Figs. V and VI are vertical sections of the lower part of the stove without the pipes.

Similar letters of reference indicate similar 35 parts in all the views.

A is the hot-blast stove or oven, having at its upper end the ordinary hot-blast pipes, B. C is a pipe in the form of a gang, connected at its upper end to the pipes B at a , and extending downwardly to a' at the base of the oven, where it receives the cold blast. The hot blast is delivered at b , which is the termination of the ordinary hot-blast pipes.

D D are the combustion-chambers, formed of fire-brick, into which the hot gases from the furnace are introduced through the medium of the pipes E, and air to combine with the gases and complete combustion is admitted through the openings e.

F F are slots through which the hot gases escape from the combustion-chambers to the interior of the oven and around the gang of pipe C before reaching the stacks D'.

G G are hollow heat-retaining blocks placed between the upper sections of the gang-pipe C, against the outer surfaces of which the hot gases impinge in their passage to the oven. As before stated, the air enters cold at a' and is delivered hot at b , it having traversed the whole length of the gang-pipe and through the different sections of the pipe B. It will be seen that both sides of the gang of pipe C are influenced by the action of heat from radiating-surfaces, the wall of the oven furnishing one radiating surface, and the combustion-chambers and heat-retaining blocks the other. The pipe C is therefore uniformly heated and cooled, and warping and distortion of the pipe prevented when the operation of this furnace is suspended and the said pipe is in process of 70 cooling.

I claim as my invention—

In a hot-blast stove or oven, the ordinary hot-blast pipes thereof, continued to the base of the said oven by means of a gang of pipe, 75 and the sections of the said gang separated by heat-retaining blocks, and combustion-chambers having means for the entrance of hot gases from the furnace, and apertures for the exit of the said gases to the interior of the 80 said oven, all combined substantially as and for the purpose specified.

H. WILLIAM ELLICOTT.
